UNITED STATES PATENT OFFICE

PAUL E. HELLER, OF NEWARK, NEW JERSEY

PNEUMATIC CONVEYER

Application filed September 16, 1927. Serial No. 219,860.

This invention relates to pneumatic conveyers or elevators of the type adapted for the discharging of grain from barges, railway cars or other carriers, and operative to 5 convey the grain to an elevated position, such as is required in the storing of grain within elevator structures.

An important object of the present invention is to accomplish the delivery of the grain 10 by means of a pneumatic conveyer in an improved condition as related to the action of a pneumatic conveyer apparatus as heretofore employed. In this connection it will be understood that in the pneumatic conveying 15 of grain to the substantial heights of practical requirements, the suction through the service or delivery conduit is such as to impart a very high velocity to the particles of grain impelled thereby. As a result of the 20 high velocity, the delivery of the grain within the expansion tank is difficult of accomplishment without injury to the grain, which has been an objectionable factor in the apparatus as heretofore employed.

In accordance with my present invention, there is provided at the upper end of the service conduit a baffle box or delivery end structure of improved form and having a downwardly directed discharge opening within 25 the expansion tank and is formed at its upper end to provide a baffle or buffer chamber for confining the grain at the end of its travel and within which a volume of grain will be held in suspension during the operation to 30 act as a cushion for and to receive the impact of the grain stream at the delivery end of the service conduit. As a result, there is provided an effective cushioning means operative to allow delivery of the grain with substantial elimination of the injury to the particles thereof as commonly experienced.

My present improvements further include an improved flexible or adjustable connection between the service or delivery conduit 40 and the expansion tank of an arrangement

providing for the continuity of the service conduit in a straight line and of uniform diameter throughout its full length. This arrangement allows of high operating efficiency and avoids objectionable expansion within 50 the conduit, which would interfere with maintaining the velocity and which is characteristic of many types of ball joints as heretofore employed.

My improved apparatus further includes 55 an improved design and arrangement of intake nozzle for the service conduit adapted to increase the operating efficiency and to facilitate the discharge of grain.

The foregoing other features and advantages of my improved conveyer apparatus will be more fully understood by reference to the accompanying drawings, wherein like reference numerals are applied to the corresponding parts in the several views.

In the drawings:

Figure 1 is a diagrammatic view in side elevation illustrating the general structural arrangement of a pneumatic conveyer installation, of the type in connection with which 70 the features of the present invention are desirably employed;

Figure 2 is a detailed view in side elevation, illustrating my improved discharge or baffle box and associated structure;

Figure 3 is a view of the discharge end portion of the service conduit in central longitudinal section;

Figure 4 is a detailed view of the adjustable drum connection between the service conduit 80 and expansion tank;

Figure 5 is a view in side elevation of the improved intake nozzle structure; and

Figure 6 is a view thereof in end elevation.

Referring particularly to Figure 1 of the drawing, wherein there is diagrammatically shown a typical installation, 1, indicates a suitable supporting structure, 2 the usual expansion tank within which the grain is delivered from the service or delivery conduit 90

3 by the operation of suitable air pumps connected to exhaust the air from the upper part of the expansion tank through an air line or conduit 4. At 6 there is indicated a barge 5 from which the grain is to be discharged by means of the usual intake nozzle or nozzles 7, connected to the service conduit by means of the usual flexible hose 8. The expansion tank 2 is provided with the usual bottom hopper 9 and discharge valve 10 for delivery of the grain to a belt conveyer 11 for conveying the grain to the grain elevator or other receiving point.

In accordance with an important feature 15 of the present invention, the delivery end of the service conduit 3 is positioned within the expansion tank, and is provided with a baffle box or buffer discharge chamber 14, formed with a downwardly directed discharge opening 15. The baffle box, as shown, may desirably be of cylindrical cross section and has a closed upper end wall 16, forming a buffer chamber positioned above the discharge opening 15, within which the grain will be carried 25 by velocity and from which it will be discharged by gravity and by reason of the air current through the opening 15, as will be readily understood. In the operation, by reason of the high velocity, a volume of grain 30 will be constantly maintained within the buffer chamber, and by reason of its suspension, will have a desirable cushioning effect upon the grain, whereby the delivery will be accomplished in a materially improved manner and 35 without injury to the grain particles. A rubber composition or other cushioning disk 17 may be supported within the buffer chamber at the uppermost end thereof, as shown, to further insure against injury of the grain 40 particles.

A further feature of my present invention, and as best shown in Figures 2 and 4, consists in the provision of an improved form of adjustable connection between the expansion 45 tank and the service conduit which is particularly designed to maintain a uniform cross-sectional area and rectilinear direction of the latter. The adjustable connection as shown 50 comprises a circular supporting drum 18 rigidly secured to the expansion tank to be supported thereby, the supporting drum being formed with inner and outer enlarged openings 19 and 20 and is provided with closed end walls 21. Fitted within the supporting 55 drum there is provided an annular or cylindrical movable drum portion 22. This inner drum is arranged to have a close rotatable fit within the outer drum and is provided with a tubular pipe or opening therethrough forming 60 a part or continuation of the service conduit opening and to which it is connected at the lower end and to the buffer box at the opposite or upper end. As a result, the service conduit is supported to be adjustable vertically by means of a pivotally supported boom

24 to which the conduit is connected at its outer end, the boom being adjusted by means of a suitable cable 25. This arrangement provides for the desired swinging of the service conduit while maintaining a rectilinear passage for the grain, thereby insuring high efficiency.

My improved apparatus further includes an improved design and structural arrangement of the intake nozzle adapted to facilitate the discharge of the grain from a barge or railway car, and particularly to enable the full discharge of the grain from vessel bottoms, corners, etc. As shown in Figures 5 and 6, the nozzle is of general tubular cross-section and of substantially semicircular form, and provided with a grain intake opening 28 angularly disposed with relation to its discharge end portion 29 to which the service hose is attached. At its end opposite to the discharge portion 29, it is formed with a substantially straight portion 30 and at its return bend extremity 31 it is provided with an air intake or open end portion 32, to which is fitted an adjustable shutter 33 providing for adjustment of the air intake areas. The latter feature is particularly advantageous in allowing convenient manual adjustment of the air intake for properly proportioning the air volume with relation to the density of grain being handled, so as to obtain high operating efficiency. The nozzle is provided with opposite handles 35 and a manipulating lever 36. The improved form of intake nozzle as shown, wherein the air passage is of curvilinear form contributes to the efficiency of the operation by avoiding abrupt turning or reversal of the air current and accordingly avoiding the resistance which would result therefrom.

While I have described the improved pneumatic conveyer apparatus as particularly applicable to the conveying of grain, it will be understood that it may be likewise employed for the conveying of other granular material, and further that the several features of the invention as defined in the appended claims may be varied in form and arrangement without departing from the scope of the invention.

Having described my invention, I claim:

In a pneumatic conveyer the combination with a service conduit and of an expansion tank at its upper or delivery end portion, of an adjustable connector between said service conduit and tank to permit swinging of the conduit with relation to the tank, said connector consisting of an outer drum supported upon the tank and formed with inner and outer enlarged openings, a circular bearing member rotatably fitted thereto and formed with a conduit connected with and forming a part of the service conduit in axial alignment therewith and providing a passage of substantially uniform cross-sectional area and a baffle box positioned to form the delivery

end of the service conduit, said baffle box having a downwardly directed discharge opening and a buffer chamber positioned above said opening to receive the grain at the end of its upward travel and to hold a volume in suspension for the cushioning of the succeeding grain, substantially as described.

Signed at Newark, in the county of Essex and State of New Jersey, this 20th day of June, A. D. 1927.

PAUL E. HELLER.
